COMBINED BODY AND CHASSIS
UNDERFRAME

Joseph Ledwinka, Philadelphia, Pa., assignor to
Edward G. Budd Manufacturing Company,
Philadelphia, Pa., a corporation of Pennsyl-
vania

Application December 6, 1937, Serial No. 178,315

8 Claims. (Cl. 296—28)

The invention relates to a combined chassis and body underframe structure for vehicles and particularly for automobiles.

It is an object of the invention to create such a combined underframe structure which is strong and durable, simple in construction, easy to manufacture, and light in weight. One important object of the invention is also to create a combined chassis and body underframe structure which is especially adapted for different types of body superstructures.

These and other objects are attained in large by the use of upwardly opening channel shaped longitudinal side sills, following approximately the lower longitudinal margins of the body superstructure and by the use of a sheet metal flooring overlying and closing the mouth of said channels thereby forming box sectional sills. The body superstructure is then fastened to the lateral margins of said flooring. It is obvious that the same channel shaped sills may be used for different types of body superstructures. This means considerable advantages as the large dies for the channel shaped sills are very expensive and as the manufacturer needs only to keep a stock of one underframe structure for the different types of superstructures. It has been a disadvantage of many hitherto known combined underframe structures that they were only adapted for one special type and construction of superstructure and that rather slight changes in dimensions or design made necessary such alterations of the underframe structure that new dies had to be procured.

Other and further objects and advantages of the invention and the manner in which they are attained will become apparent from the following detailed description and the accompanying drawings in which:—

Fig. 1 is a diagrammatic side elevation of a closed four-door motor car body;

Fig. 2 is a plan view of the combined chassis and body underframe and a section of the body superstructure taken along the line 2—2 of Fig.

1; and

Figs. 3 to 7 are cross sectional views taken along the correspondingly numbered section lines of Fig. 1.

The car shown in the drawings comprises longitudinal side sills generally designated by the numeral 10. These sills extend from the front end to the rear end of the car. The middle section of these sills is outwardly curved in plan view so as to follow the lower margin of the body superstructure generally designated by the

numeral 11. The forward and rearward ends of the sills 10 are upwardly offset in side elevation so as to allow the upward movement of the front axle and the rear axle whereas the middle section in the region of the door openings 12 is situated relatively low. Each of the sills 10 consists mainly of an upwardly opening channel having a bottom wall 13, an outer side wall 14 with an outwardly directed upper flange 15 and an inner side wall 16 with an inwardly directed 10 flange 17. The forward sections of the sills 10 are connected by transverse members 18, 19 and 20. The mouth of the forward ends of the sills 10 is closed by cover strips 21 fastened as by welding to the lateral flange 15 and 17. The 15 outer margin of each strip 21 is provided with a downwardly depending flange 22. These strips 21 extend from the forward end of the sills 10 to about the region of the cowl 23 and the front post 24 of the body superstructure.

Rearwardly of the ends of strips 21 the mouth of the sills 10 is closed by the lateral marginal parts of a flooring 25. The marginal parts of this flooring are fastened as by welding to the lateral flanges 15 and 17 of the sills 10 and are provided with a downwardly depending flange 26 forming a continuation of flange 22 of the strips 21. Said flooring 25 extends from the cowl region to the rearward end of the car where the side sills are additionally interbraced by a 30 cross member 27. The flooring 25 may consist of one integral stamping or may be subdivided in longitudinal and/or transverse direction and may overlap to a certain extent the rear ends of strips 21. In the longitudinal middle plane of the car 35 the flooring is provided with a tunnel 28 for the propeller shaft. In the region of the rear door posts 29 the flooring forms the rear seat support 30 and behind this support a mold 31 is provided for the reception of the lower part of a spare 40 wheel (not shown).

In the region of the driver's seat an opening 32 is provided in the flooring 25 on each side of the tunnel 28. Below these openings 32 a transverse plate 33 extends from the one side of the car to 45 the other side. The longitudinal margins of this plate 33 are provided with flanges 34 angle shaped in cross section and these flanges are fastened as by welding to the underface of the bottom walls 13 of the sills 10. The side walls 50 of the tunnel 28 are downwardly extended beyond the plane of the flooring 25 and the lower margins of the walls are fastened by laterally bent-off flanges 36 to the upper face of plate 33. Transverse walls 37 are inserted between the in-

ner walls 16 of the sills 10, the vertical walls 35 of the tunnel 28, the transverse margins of the openings 32 in the flooring 25 and the transverse outer margins of the plate 33 and are fastened to these members. Hereby a casing is formed on each side of the tunnel 28. Above the flooring 25 the transverse walls 31 are continued by transverse walls 38 extending, however, across the tunned 28 and across the upper side of the 10 sills 10. The upper margins of the transverse walls 38 are connected by a substantially horizontal wall 39. The wall 39 and the wall 38 may be formed from one integral stamping. The lower margins of the walls 38 are fastened as by welding to the flooring 25, the flanges 15 and 17 of the sills 10 and to the upper part of the tunnel 28. The upper wall 39 is provided with one opening 40 on each side of the tunnel 28 giving access to the interior of the boxes formed by the 15 side sills, the tunnel and the transverse walls 33, 37, 38 and 39. These boxes may be used for housing the storage battery, tools or the like. The walls 38 and 39 form the front seat support.

The body superstructure may comprise unitary 20 side wall stampings each enclosing door openings 12, a side window opening 41, one side wall of the cowl 23 and the rear wheel housing 42. This outer panel designated in general by the numeral 43 is provided along its forward margin, 25 its lower margin and along the margins of the floor openings with inwardly directed flanges 44, 45 and 46 respectively and the margins of these flanges in their turn are provided with bent-off flanges 47, 48 and 49 respectively. The last 30 named flanges are seated against and fastened as by welding to an inner sheet metal paneling 50 so that in the threshold and cowl regions box sectional structures are formed. The inner paneling extends forwardly beyond the cowl 23 35 forming thereby the vertical wall 51 of the front wheel housing.

The rear wheel housing 42, the inner reinforcing panel 50 and the front wheel housing 51 of the body superstructure are provided with an 40 outwardly directed offset 52 being spaced from and extending parallel to the lowermost edge of said parts. The angle formed on said members by the offset 52 and adjacent marginal parts 53 is seated on the angle formed by the flooring 25 45 and its marginal flange 26 or by the covering strip 21 and its flange 22 respectively. The marginal parts 53 are fastened as by welding to said depending flanges 26 and 22 respectively.

So as to further strengthen the connection between the body superstructure and the flooring 25 and the longitudinal sills 10, the lateral margin of the walls 38 and 39 of the front seat support are fastened by means of flanges 54 to the inner side wall member 50 and the flanges 48 55 and 49 of the outer side wall member 43. The walls 33, 35, 38 and 39 arranged below the front seat form thereby a box sectional cross member of great cross sectional area and correspondingly great strength. This box sectional transverse 60 structure strengthens very efficiently the entire combined body and chassis structure against bending and torsional stresses.

The connection between the underframe structure and the body superstructure may be further 65 strengthened by brackets 55. One arm 56 of such bracket extends across the mouth of the sills 10 and is fastened to its flanges 15 and 17 and to the upper surface of the flooring 25. The other arm 57 of said bracket is fastened to the inner panel 50 of the body superstructure which may

in this region be additionally reinforced by a member 58. Although such brackets 55 are shown in the drawings only in the region of the intermediate door posts, such brackets may of course also be applied in other regions especially in the region of the cowl, of the front posts, and of the rear posts.

The main portion of the flooring 25 is arranged in the plane of the upper flanges 15 and 17 of the side sills 10 but this flooring may also be offset 10 downwardly with respect to said flanges. Such downward offset 59 of the central part 60 of the flooring 25 is shown in Fig. 7. All members of the embodiment shown in the drawings and described before are intended to be stamped from sheet 15 metal but the invention is not restricted to this material only. The longitudinal sills 10 may each consist of one integral piece or may be composed of several pieces. Also other members, i. e., the inner panel 50 and the front wheel housing wall 51 may either be formed as integral stampings or may be composed of several stampings. Many changes of the constructional details of the embodiment are possible without departing from the spirit of the invention which 20 modifications shall be protected by the appended claims.

What I claim is:

1. In a combined body underframe and chassis structure for an automobile, one sill member 30 along each longitudinal side of such structure, each sill member being in the form of an upwardly opening channel and following in plan view substantially the lower side contours of a body superstructure to be fastened to said underframe 35 and chassis structure, said sill members extending beyond the region of said body superstructure thereby defining laterally a motor space; a sheet metal flooring in the region of said body superstructure extending over the entire width 40 of the body and closing in this region by its horizontal marginal parts the open mouths of said sill members, and a separate horizontal sheet metal strip for each sill member closing the mouth thereof in the region of said motor space. 45

2. In a combined body underframe and chassis structure for an automobile, a sheet metal flooring extending over the entire width of the body, upwardly opening channel shaped longitudinal sills following in plan view substantially 50 the lower marginal contours of separately manufactured side wall members of a body superstructure to be combined with said underframe and chassis structure, the mouths of said sills being closed by said sheet metal flooring, said 55 flooring being provided along each of its outer lateral margins immediately adjacent the outer edge of the respective sill with a substantially vertically bent off flange, said flange forming connecting means for said side wall members 60 and forming a reinforcement of said flooring and of the body underframe and chassis structure.

3. In a combined body underframe and chassis structure for an automobile, a sheet metal flooring, upwardly opening channel shaped longitudinal sills following in plan view the lower marginal contours of a body superstructure to be combined with said underframe and chassis structure, the mouths of said sills being closed by said sheet metal flooring, said flooring being 70 provided along each of its outer lateral margins immediately adjacent the outer edge of the respective sill with a downwardly bent off flange, said flange forming connecting means for said superstructure and forming a reinforcement of 75

said flooring and of the body underframe and chassis structure, said flanges forming furthermore means for concealing from view the upper part of said sill members and of their outer connection with the floor stamping. 5

4. In a combined chassis and body underframe structure, a sheet metal flooring, side sills following the lower marginal contours of a body superstructure to be fastened to said underframe structure by being outwardly bulged in plan view in the region between the front and rear wheels and being fastened to said sheet metal flooring, a body superstructure comprising box sectional threshold portions, said threshold portions being arranged throughout their lengths substantially above the level of said flooring and of said side sills of the underframe structure and fastened to the lateral margins of said flooring. 10

5. In a combined chassis and body underframe structure, a sheet metal flooring, upwardly opening channel shaped longitudinal side sills following the lower marginal contours of the body by being outwardly bulged in plan view in the region between the front and rear wheels, the mouths of said sills being closed by said sheet metal flooring, a body superstructure comprising a vertical post, a bracing member extending across the opening of the adjacent channel shaped sill and being fastened to both side walls thereof and to 15 said post.

6. In a combined body underframe and chassis structure, a sheet metal flooring, longitudinal side sill members fastened to said flooring, a transverse member connecting said side sill members, said sill members and said transverse member extending below said flooring, said transverse member being in the form of an upwardly opening trough, this trough comprising a bottom wall and upstanding side walls, the ends of this trough being fastened to said sill members and its side walls being fastened to said flooring, an opening 20
